UNITED STATES PATENT OFFICE.

JOSEPH EDMOND BLYTHE, OF BOONEVILLE, MISSISSIPPI.

BRUSH.

No. 891,978.

Specification of Letters Patent.

Patented June 30, 1908.

Application filed January 29, 1908. Serial No. 413,311.

To all whom it may concern:

Be it known that I, JOSEPH EDMOND BLYTHE, a citizen of the United States, residing at Booneville, in the county of Prentiss 5 and State of Mississippi, have invented a new and useful Brush, of which the following is a specification.

This invention relates to drying attachments for scrubbing brushes, and has for its 10 object to provide a squeegee attachment which will not only force the water into a tank provided for that purpose, but will hold and prevent the same leaking out.

The object of the present invention is to 15 provide a squeegee with a support or brace which will not only preserve its elasticity but will positively force it over the opening of the tank each time the pressure exerted to force it in an opposite direction is removed.

20 With this and other objects in view, as will more fully hereinafter appear, the invention consists in certain novel features of construction and arrangement of parts, hereinafter fully described, illustrated in the accompanying 25 drawings, and particularly pointed out in the appended claims, it being understood that various changes in the form, proportions, size and minor details of the structure may be made without departing from the spirit or 30 sacrificing any of the advantages of the invention.

In the accompanying drawings:—Figure 1 is a front view of a brush having the tank and squeegee mounted thereon. Fig. 2 is a 35 transverse sectional view on the line 2—2 of Fig. 1. Fig. 3 is a perspective view of the device. Fig. 4 is a modification of Fig. 2. Fig. 5 is a bottom plan view taken on a line 3—3 of Fig. 4.

40 Similar numerals of reference are employed to indicate corresponding parts throughout the several figures of the drawings.

1 designates an oblong tank, preferably formed of a single sheet of metal bent at right 45 angles to the direction of its length, forming the walls 3 and 4. The pieces 2 forming the end walls for the tank are riveted to the sides 3 and 4. The tank is secured to the head by the bolts 5 and thumb screws 6, the bolts extending 50 through apertures 7 in the body of the brush and similar apertures 8 extending transversely through the block 9 and clamped in place by the thumb screws 6. The head is 55 triangular in shape, having a central aperture on its outer face for the reception of a

handle, (not shown), the inner face forming the rear wall of the tank 1. On the inner end of the lower face of the head is formed a rabbet 10 extending the entire length of the block, and of a depth to accommodate the 60 squeegee 11, the latter made of india rubber and having its inner side secured in said rabbet by nails or screws 12.

The outer side of the squeegee projects beyond the rabbet 10 and the outer wall 4 of 65 the tank 1, the projecting portion 13 extending beyond the outer face of the wall 4 having one of its faces contacted with the lower end of the wall 4. Normally the squeegee will occupy this position, but the constant 70 bending it must necessarily undergo by being forced over the surface of floors, windows, and the like, will, in a short time, cause it to lose its elasticity with the result that it will fail to contact with the edge of the wall 4. 75 It can be readily seen that in such position, its usefulness will be destroyed. To overcome this defect in the present device there is employed the resilient rectangular metallic strip 14, forming a support or platform of 80 slightly less length and considerably less width than the squeegee. The strip is disposed on the lower face of the squeegee intermediate the sides and ends, and is retained in this position against lateral and longitudinal 85 movement by a rod 15, one end of which is turned at right angles and projects upwardly through a perforation adjacent one end of the squeegee and lying parallel with and on the exterior of the end wall 2. 90

The rod is held in close contact with the strip or platform by means of the helical springs 17. In use there may be as many of these springs employed as thought necessary. In the present instance the device is shown 95 with three, one adjacent either end, and the third occupying the central position in the tank. The springs are disposed within the tank 1 and have one end projecting through apertures in the wall 3 thereof and secured on 100 its outer face, as shown, the opposite end of each spring passing through alining perforations of the squeegee and strip and encircling the rod 15, forcing the squeegee through the rod and strip up against the end of the tank 105 wall 4, as clearly shown in Figs. 1, 2 and 3.

It can be readily seen that a force applied to separate the squeegee from the end of the tank will be transmitted to the springs through the rod 15, placing the springs and 110

strip 14 under tension, and when this strain is removed, the squeegee is not only assisted in returning to its normal position, but hastened, through the energy stored in the 5 springs and strip.

The device may be used connected to or without the brush, and when the bolt 5 and the thumb nut 6 are detached, that part of the device including the block 9, tank, squeegee, springs and platform are removed from 10 the brush and tank.

When the parts occupy the position shown in Figs. 1, 2 and 3, the closed face of the metallic strip 14 rests on the back of the brush 15 and when the parts are clamped together by the bolt and screw, each time the squeegee is forced away from the wall 4, there will be a relative bending of the strip 14 and spring 17.

Figs. 4 and 5 show a modification of the 20 device, the parts being the same with the exception that the helical springs and bolts are not employed and to compensate for the former, are springs 19 having one of their 25 ends secured in a longitudinal groove formed in the bottom of the head and the opposite ends projecting therefrom at right angles to and beyond the sides of the brush. To these springs is riveted or otherwise secured the metallic strip 20 functionally corresponding 30 with the strip 14. Beneath the springs 19 are screws 21 extending through apertures in the back of the brush, and the ends abutting the face of the springs. The function of these 35 screws is to keep the outer ends of springs 19 in contact with the inner portion of the squeegee.

The operation of the device is as follows:— After the floors, windows or the like have 40 been scrubbed, the handle, (not shown), to which the brush is attached, is turned until the edge of the squeegee rests on the surface just scrubbed. The device is then drawn towards the operator a sufficient pressure applied to force the squeegee away from the 45 wall 4 and over the wet surface. During this movement the water on the surface of the floor and window will be forced up into the tank.

I claim:—

1. In a device of the character described, 50 the combination of a brush having a head secured to the back thereof and a squeegee fitted between the base of the head and back of the brush and projecting in advance thereof, a metallic tank having one edge normally 55 in contact with said squeegee and another edge secured to the said head, an independent support for the squeegee having its inner edge interposed between the back of the brush and squeegee and its outer edge lying 60 adjacent the outer edge of the squeegee.

2. In a device of the character described, 65 the combination of a brush having a head secured to the back thereof and a squeegee fitted between the base of the head and back of the brush and projecting in advance thereof, a metallic tank having one edge normally 70 in contact with said squeegee and another edge secured to the head, a resilient support for the squeegee having its inner edge interposed between the back of the brush and squeegee and a yielding connection between the platform and tank.

3. In a device of the character described, 75 a brush, a block mounted thereon, a bolt extending through said block, a thumb screw on said bolt, a tank, a squeegee having a surface in contact with one end of said tank, a resilient platform having a portion disposed 80 between the brush and block, a rod on the face of said platform, a spring connecting the squeegee and platform through the rod to the tank, and relative yielding between the squeegee platform and spring when the squeegee 85 is forced from contact with the wall of the tank, said spring and platform aiding to return the squeegee to its normal position, as described.

In testimony that I claim the foregoing as my own, I have hereto affixed my signature 90 in the presence of two witnesses.
